UNITED STATES PATENT OFFICE.

FREDERICK SANFORD SEYMOUR, OF MANCHESTER, IOWA.

STOVE OR FURNACE FEED.

1,183,909.

Specification of Letters Patent.

Patented May 23, 1916.

Application filed May 22, 1914. Serial No. 840,217.

To all whom it may concern:

Be it known that I, FREDERICK S. SEY-
MOUR, a citizen of the United States, and re-
siding in Manchester, in the county of Del-
aware and State of Iowa, have invented a
new and Improved Stove or Furnace Feed,
of which the following is a full, clear, and
exact description.

An object of my invention is to provide
10 an automatic coal feeder particularly
adapted for feeding coal to small heating
stoves, ranges, house boilers, tank heaters,
feed cookers, and the like, in which there is
not a very large consumption of coal.

15 The invention is designed to be built with
the stove, range or furnace, in the manufac-
ture of the latter, or to be made up as a sep-
arate attachment applicable to stoves, etc.,
already manufactured.

20 It is a further object of my invention to
provide an automatic feed, the action of
which may be regulated so that the period
of operation will extend over any desired
number of hours.

25 It is also an object of my invention to pro-
vide for the feeding of a small quantity of
coal during the early hours of the night
only, or for the feeding of a given quantity
of coal during only the later hours of the
30 night or early morning.

Further objects of my invention are to
promote economy in the consumption of fuel;
to minimize or entirely obviate the produc-
35 tion of smoke and soot; to provide a feed
that will result in an even fire without the
use of a thermostat; to provide an attach-
ment that will be effective with either hard
or soft coal; to save labor in attending to
40 the firing of a stove or furnace; to promote
cleanliness in lessening the dirt resulting
from the burning of coal, particularly bi-
tuminous coal; and to prevent explosions
in stoves due to the accumulations of explo-
sive gases therein.

45 An object of the invention furthermore,
is to provide an automatic feed improved
in various particulars, to the end that effi-
ciency of operation may be promoted as
well as economy of manufacture and sim-
50 plicity of adjustment and control.

The invention will be particularly ex-
plained in the specific description fol-
lowing.

Reference is to be had to the accompany-
55 ing drawings forming part of this specifi-
cation, in which similar characters of refer-

ence indicate corresponding parts in all the
views.

Figure 1 is a longitudinal vertical section
of an automatic feed embodying my inven-
tion, showing the same in connection with
a heating stove; Fig. 2 is a sectional plan
view on line 2--2 of Fig. 1; and Fig. 3 is a
fragmentary side elevation with parts
broken away, and others in section, of the
escapement mechanism arranged as in
Fig. 1.

Referring more particularly to Figs. 1
and 2, a box-like coal magazine 10 is
mounted on top of the heating stove A, said
magazine being preferably oblong. The
magazine may be secured in any suitable
manner to the top of the stove or heater
A. As here shown, the magazine is sup-
ported at the front by a bracket 11, and at
75 the rear by a feed tube 12 constituting a
feeding opening leading downwardly
through the top of the stove, from the mag-
azine. Extending downwardly below the
feed tube 12 is a deflector 13, to direct to-
80 ward the center of the stove or heater, the
coal falling through the feed tube. The
top of the magazine may have any suitable
removable cover 14, for charging the maga-
zine with a supply of coal.

85 In order to feed the coal from the maga-
zine through the feed tube 12, a plunger or
follower 15 is provided and has guided
longitudinal movement in the magazine by
means of a longitudinal guide rod 16, which
90 is fastened at its ends to the front and back
of the magazine and passes through a trans-
verse hole 17 in the follower 15 and also
through a hole 18 in a depending lug 19
95 formed on a forwardly extending arm 20
on the follower. The arrangement serves
to give a parallel guided movement to the
follower. To advance the follower, a chain
21 is connected with the same and extends
100 in the present instance, over a sprocket
wheel 22, the shaft 23 of which turns in a
standard 24 and bracket 24^a. Any suitable
means may be provided for exerting a pull
105 on the chain 21. I have shown a weight 25
hung on the free end of the chain, said
weight serving to advance the follower, sub-
ject to an escapement mechanism provided
for the purpose.

110 The escapement mechanism comprises a
spur gear 27 and a train of pinions 28, in
suitable number and of a form and arrange-
ment of an ordinary clock train. A pendu-

- lum 29 carries an adjustable weight 30, provided with any suitable member, as at 31, which projects at the side toward the pendulum sufficiently to engage in any one of a series of vertical slots 32. A pallet 33 is actuated by the pendulum, in the well known manner of such devices, and engages an escapement wheel 34 driven by the last pinion in the clock train.
- 10 To return the follower to the front of the magazine after a charge of coal has been fed to the furnace, and permit another supply of coal to be deposited on the bottom of the magazine in front of the follower, a chain 35 is connected with the follower and is secured to a winding drum 36. In the arrangement shown the drum is mounted on a shaft 37 suitably journaled in brackets 38 or equivalent members of the magazine.
- 15 20 The shaft 37 is adapted to receive a detachable crank handle in the well known manner, the handle being indicated by dotted lines at 39. To retard the action of the drum and prevent slack in the chains when 25 the supply of coal has become exhausted, a suitable brake may be provided for the drum. As here shown, a plate spring 40 is provided for the purpose.

In the arrangement shown in Fig. 1, the chain 21 passes downwardly from the sprocket 22 through the flue or stove pipe 41, the latter being provided with a guide tube 42 extending vertically therethrough for the passage of the chain downwardly to 35 a connection with the suspended weight 25.

The construction provides a combined fuel feed tube 12 and stove pipe collar which enables me to apply the magazine and its feed devices to stoves presenting no fire door on the side or front, of which stoves there are vast numbers; the lower end of the feed tube 12 will fit any of the usual stove pipe collars or like expedients on the top of the stoves in question and the lateral flue 41 40 serves to connect the usual stove pipe section to the feed tube 12.

By the described construction the magazine 10 may be substantially filled with coal from the follower 15 to the feed tube 12, and 50 the feed device may be started at any time by swinging the pendulum, after which the feed will be continuous, being gradual un-

til the follower reaches the feed tube and has delivered all the supply. By then winding in the chain 35, the follower may be returned to the initial position to act again.

It will be clear that if the coal is to be fed only during the early part of the night, the follower will be advanced to a position about central of its total path of travel and 60 only a limited amount of coal placed in front of the follower so that the supply will be exhausted in the required period and no more will be fed during the remainder of the night. On the other hand, if the follower be 65 returned to a position adjacent to the outer end of the magazine and only a limited quantity of coal be placed directly in front of the follower, then obviously there will be no coal fed through the feed tube 12 until 70 a period has elapsed sufficient to bring the front of the coal to the said opening. Thus coal will not be fed during the early part of the night, for instance, but only during the later hours of the night or the early morning. The speed of the feed may be regulated by raising or lowering the weight 30 on the pendulum 29.

Having thus described my invention, I claim as new, and desire to secure by Letters 80 Patent:

A fuel feed means for stoves, furnaces and the like, comprising a magazine adapted to receive a supply of fuel on the bottom thereof and formed with a discharge outlet in 85 the bottom near one end, a follower movable in said magazine toward and from the said outlet, means for advancing the follower to force the fuel to the outlet, and a combined fuel feed tube and stove pipe collar connected at its upper end with the magazine at the outlet and adapted at its lower end to connect with the stove, there being a lateral branch on said feed tube between the upper and lower ends thereof to receive a 90 stove pipe section.

In testimony whereof I have signed my name to this specification in the presence of two subscribing witnesses.

FREDERICK SANFORD SEYMOUR.
